COLLAPSIBLE HANGER

George Marbit, Brooklyn, N. Y.

Application June 23, 1950, Serial No. 169,827

3 Claims. (Cl. 223—94)

1

This invention relates to garment hangers and, more particularly, to a folding hanger adapted to be carried in the pocket.

One object of the invention is the provision of a garment hanger so constructed that the same is foldable into a compact bundle adapted to be carried in a pocket in the same manner as a fountain pen.

Another object of the invention is to construct said hanger so that the same is rigidified in the form of a garment hanger by the positioning of the hook which is utilized to support the same.

A still further object of the invention is to construct the hanger so that the same is capable of being manufactured economically.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the hanger of the invention.

Fig. 2 is a side view of the hanger in folded position.

Fig. 3 is an enlarged fragmentary detail side view of a hinge of the hanger.

Fig. 4 is a fragmentary sectional view on line 4—4 of Fig. 1.

Fig. 5 is a sectional view on line 5—5 of Fig. 1.

Fig. 6 is a fragmentary sectional view on line 6—6 of Fig. 4.

The hanger, according to the present invention, includes a pair of inner metal strips 10 and a pair of outer metal strips 11. The strips 10 are connected together at their proximate ends by a pair of hinges 12 secured to the under faces of the strips, see also Fig. 5. The far ends of the strips 10 are connected by hinges 13 with the inner ends of the strips 11. The ends of strips 10 and 11 connected by the hinges 13 are angled as shown at 14 in Fig. 3 so that relative angular movements of the parts are limited to substantially less than 180°. The construction is such that when the strips 10 are arranged in the angular positions shown in Fig. 1 the strips 11 are held in horizontal positions by the angled edges 14.

The hanger is provided with a hook member 15 by which the same can be supported, the stem of said hook member, see Figs. 4, 5 and 6, passing through the space between the proximate

ends of the strips 10 and between the hinges. The lower end of the hook member stem is slotted to receive the upper edge of a wedge retainer member 16 to which the stem is secured by means of a rivet pin 17. As best shown in Figs. 4 and 5, the retainer member 16 is formed of sheet metal, and the strips 10 are provided with notches or grooves 18 in which the inclined side edges of the retainer member are seated.

10 The construction is such that retainer 16 by its shape and engagement therewith, retains the strips 10 in the desired angular positions against the force of downward pressures such as would be exerted by a coat supported thereon. At the same time the angled edges 14 maintain the strips 11 horizontal against the force of said downward pressures. It will be seen therefore, that the hanger provides a rigid, formed support for a garment such as a coat.

15 The hanger can, however, be folded into the arrangement shown in Fig. 2 for carrying the same in the pocket for use in restaurants and the like. It is to be noted that in folded position the hook member 15 is adapted to coact with the edges of the strips 10 and 11 in clipping the device in the pocket.

20 To fold the hanger the angular relationship between the strips 10 is increased to free the retainer 16 from the notches 18, the strips 11 are folded up against the strips 10, the hook member turned 90° to position retainer 16 parallel with the several strips, and the strips 10 folded together. The hook member then is depressed moving the retainer 16 down between the strips 10 reducing the length of the folded hanger and bringing the end of the hook portion below the upper edges of the strips 10 and 11 so that it can act as a pocket clip.

25 It will be noted in Fig. 2 that the hinges 12 provide sufficient room between the strips 10 for said hook member 15 and retainer 16. Preferably the hinges 12 and 13 are tight so that friction will hold the several parts in their folded positions.

30 While I have illustrated and described the preferred embodiment of my invention, it is to be understood that I do not limit myself to the precise construction herein disclosed and the right is reserved to all changes and modifications coming within the scope of the invention as defined in the appended claims.

35 Having thus described my invention, what I claim as new, and desire to secure by United States Letters Patent is:

40 1. A folding garment hanger comprising a

2

pair of inner strip members the proximate ends of which are spaced a short distance apart, a pair of hinges on the under sides of said strips and connecting said proximate ends, there being a lateral space between the hinges, a pair of outer strip members, a hinge located on the upper sides of and connecting each inner strip with an outer strip, the proximate edges of adjacent inner and outer strips being angled to limit relative angular movements of the strips, a hook member situated transversely with respect to the strips and having a stem extending through the space between the inner strips and between the first said hinges, said stem having a slot in its lower end, and upwardly inwardly tapering retaining sheet member having its upper edge in said slot, and a pivot pin passing through the retaining member and the stem to pivotally connect the two, the under faces of the inner strips adjacent their hinged end having a pair of notches which receive the tapering sides of said retaining member.

2. A folding garment hanger comprising a pair of inner strip members the proximate ends of which are spaced a short distance apart, a pair of hinges on the under sides of said strips and connecting said proximate ends, there being a lateral space between the hinges, a pair of outer strip members, a hinge connecting each inner strip with an outer strip, the proximate edges of adjacent inner and outer strips being angled to limit relative angular movements of the strips, a hook member situated transversely with respect to the strips and having a stem extending through the space between the inner strips and between the first said hinges, said stem having a slot in its lower end, an upwardly inwardly tapering retaining sheet member having its upper edge in said slot, and a pivot pin passing through the retaining member and the stem to pivotally connect the two, the under faces of the inner strips adjacent their hinged end having a pair of notches which receive the tapering sides of said retaining member, whereby said retaining member maintains said inner strips in desired angular positions and the angled edges of the strips maintain the outer strips horizontal.

3. A folding garment hanger comprising a pair of inner strip members the proximate ends of which are spaced a short distance apart, a pair of hinges on the under sides of said strips and connecting said proximate ends, there being a lateral space between the hinges, a pair of outer strip members, a hinge located on the upper sides of and connecting each inner strip with an outer strip, the proximate edges of adjacent inner and outer strips being angled to limit relative angular movements of the strips, a hook member situated transversely with respect to the strips and having a stem extending through the space between the inner strips and between the first said hinges, said stem having a slot in its lower end, an upwardly inwardly tapering retaining sheet member having its upper edge in said slot, and a pivot pin passing through the retaining member and the stem to pivotally connect the two, the under faces of the inner strips adjacent their hinged end having a pair of notches which receive the tapering sides of said retaining member, whereby said retaining member maintains said inner strips in desired angular positions and the angled edges of the strips maintain the outer strips horizontal, and whereby the outer strips can be folded up against the inner strips and on disengaging said retaining member from the notches said retaining member, and the free end of said hook member lying in a plane substantially coincident with the plane of said retaining sheet member, whereby the hook member can be rotated 90° and the inner strips folded flat against one another with said retaining member therebetween, the hook member being pressed downward till its free end overlaps the upper edges of the strips to act as a pocket clip.

GEORGE MARBIT.
